E. H. Ashcroft

United States Patent Office.

E. H. ASHCROFT, OF LYNN, MASSACHUSETTS.

Letters Patent No. 79,182, dated June 23, 1868.

IMPROVEMENT IN STEAM SAFETY-VALVES.

The Schedule referred to in these Letters Patent and making part of the same.

TO ALL WHOM IT MAY CONCERN:

Be it known that I, E. H. ASHCROFT, of Lynn, county of Essex, and State of Massachusetts, have invented a new and useful Improvement in Steam Safety-Valves; and I do hereby declare that the following is a full and exact description thereof, reference being had to the accompanying drawing, and to the letters of reference marked thereon, in which like letters represent like parts.

Figure 1 is a vertical and central section of my invention.

To enable others skilled in the art to make and use my invention, I will proceed to describe its construction and operation.

My present invention may be considered as an improvement upon that for which Letters Patent of the United States were issued to me on the 21st day of April, 1868.

In the practical operation of the safety-valve referred to in said patent, above referred to, it was found that the sudden action of the valve had the tendency of drawing or lifting a considerable quantity of water, and carrying it from the boiler with the escaping steam.

One purpose of my present invention is to remedy this defect, and to this end I provide the lower part of the opening or steam-chamber *a* of the hollow base, *b*, of the valve with a foraminous diaphragm, *c*, suitably fixed therein, and through which the steam passes from the boiler to the valve.

In its passage through the diaphragm *c*, the steam is "wire-drawn," as it is termed by engineers, or caused to separate from any great quantity of moisture or water taken up by it, which will not pass through such diaphragm.

Another portion of my invention is to provide a means whereby, upon fracture or failure of the spring of the valve, the escape of steam therefrom is cut off.

In carrying out this part of my invention, I screw or otherwise secure to the lower end of the valve-stem *d* of the primary valve *g*, an auxiliary valve, *e*, and I also form in the base of the steam-chamber or passage, *a*, of the valve an auxiliary valve-seat, *f*, disposed below the primary valve, and valve-seat *g'* or *h*, as represented, the two valves being so arranged, with respect to each other and their seats, that when the primary valve *g* is controlled and operated as designed by the valve-spring *i*, the auxiliary valve *e* shall be and remain open, so as not to obstruct the action of the steam upon the primary and acting valve *g*.

The said auxiliary valve *e* is designed to perform two offices, viz, first, to break a current of water being drawn by and with the escaping steam into the open air, upon the sudden action of the steam upon the primary valve *g*; second, to act as a stop safety-valve, in the event of the fracture or breaking of the spring *i* of the valve *g*.

Should the spring *i*, which serves to depress the primary valve, become broken or disabled, the upward pressure of the steam upon the lower and auxiliary valve *e*, will force such valve tightly up to its seat, and by this means prevent the escape and loss of steam, which would otherwise find free vent into the open air, and perhaps lead to fatal results.

By referring to the accompanying drawing, it will be seen that the primary valve *g* is formed with a surrounding lip or ledge, *k*, the valve thus provided being enclosed by a second lip or ledge, *l*, formed upon or around its valve-seat, as shown in the drawing. The ledge *k* has the effect, upon the raising of the valve, of causing an accumulation of steam within the enclosure, *m*, formed by it, until such accumulation has acquired the power of lifting the valve, which it does with a sudden concussion or snap.

The lip or ledge *l* serves the purpose of preventing too great lateral spreading of the steam as it escapes in blowing off.

It will further be perceived, on referring to the drawing, that I form in the bearing-face of the primary valve *g*, an annular groove or recess, *n*. The water resulting from the condensation of steam collects within this recess or groove, and serves as a packing between the valve and its seat, when closed.

Having thus described my invention, what I claim as new, and desire to secure by Letters Patent of the United States, is—

1. The combination of the diaphragm *c*, valve *e*, valve *g*, stem *d*, with the base, *b*, and spring *i*, substantially as herein set forth.
2. The construction of the valves *g* and *e*, and the arrangement of the recesses *n* and *m*, ledges *k* and *l*, valve *e*, opening *f*, spring *i*, and diaphragm *c*, substantially as herein set forth.

E. H. ASHCROFT.

Witnesses:

EDWIN J. WRIGHT,
CHARLES E. ASHCROFT.
